UNITED STATES PATENT OFFICE.

WILLIAM E. WALKER AND GEORGE E. WILBUR, OF TAUNTON, MASS.

HEATING-STOVE.

SPECIFICATION forming part of Letters Patent No. 329,516, dated November 3, 1885.

Application filed December 22, 1884. Serial No. 150,907. (No model.)

To all whom it may concern:

Be it known that we, WILLIAM E. WALKER and GEORGE E. WILBUR, both of Taunton, in the county of Bristol and State of Massachusetts, citizens of the United States, have invented new and useful Improvements in Heating-Stoves, of which the following is a full, clear, and exact description, reference being had to the accompanying drawings, forming a part of this specification, in explaining its nature, in which—

Figure 1 represents in vertical section a heating-stove containing the features of our invention. Fig. 2 is also a vertical section at right angles to the view shown in Fig. 1. Fig. 3 is a horizontal section on the line $y-y$ of Fig. 2. Fig. 4 is a plan view of the base portion of the stove with the upper base-plate removed to show the arrangement of flues. Fig. 5 is a plan view below the line of the ash-pit plate. Fig. 6 is a vertical section of the base portion of the stove upon the line $x-x$ of Fig. 3.

The invention is represented as applied to the class of heating-stoves known as "indirect-draft heating-stoves," or stoves which have flues extending downward from the combustion-chamber to the base and from them to the uptake.

In the drawings, A is the ash-pit; B, the fire-pot; C, the combustion-chamber; D, the outer casing of the main portion of the stove, and D' the base section of the stove. E E' are downflues on either side of the stove, connecting the combustion-chamber with the base-flues $e-e'$. These base-flues extend along the sides of the base from the front to the dotted line e^2 shown in Fig. 3, and, through the openings e^3 in the ash-pit walls e^4 , connect with the base-flue e^5 beneath the ash-pit plate

e^6 . The flue e^5 extends backward upon the dotted lines e^7 , Fig. 3, to the uptake e^8 . Below the plate e^9 , forming the bottom of the flue e^5 , is the flue or passage F, the under or lower surface of which is the bottom plate, f. 45 This flue is open to the outer air at f' , (see Figs. 2 and 6,) and extends backward, and then laterally outward at f^2 , (see Fig. 6,) and enters the chamber f^3 at each of the back corners of the stove, (and the cover.) Air which 50 enters through the hole or aperture f' is heated by coming in contact with the plates which separate this cold-air passage from the base-flues and ash-pit, and it escapes through the holes f^4 in the upper base-plate at each 55 back corner. (See Figs. 3 and 6.) These holes f^4 may be closed by registers f^5 , if desired.

The inlet-holes f^6 may be provided in the back base-plate of the stove, if desired.

The grate and oven-cover, which formed a 60 part of the original application, have been withdrawn by amendment, and made the subject-matter of separate applications.

Having thus fully described our invention, we claim and desire to secure by Letters Patent 65 of the United States—

1. The combination, in a heating-stove, of the fire-pot B with the flues $e-e'-e^5$, the cold-air passage F f^2-f^3 , and outlets f^4 , all substantially as and for the purposes described. 7c

2. In a heating-stove, the combination of the fire-pot B with the base-section D', having the flue-plates $e^4-e^6-e^9-f^3$, which form the base-flues and cold-air passages, substantially as specified.

WILLIAM E. WALKER.
GEO. E. WILBUR.
